UNITED STATES PATENT OFFICE.

OLIVER C. G. BRETELL, OF WILKINSBURG, AND JOHN F. BAILEY, OF EDGEWOOD,
PENNSYLVANIA.

DESIGN FOR A URINAL.

41,401.

Specification for Design.

Patented May 23, 1911.

Application filed September 16, 1909. Serial No. 518,122. Term of patent 14 years.

To all whom it may concern:

Be it known that we, OLIVER C. G. BRETELL, a citizen of the United States, residing at Wilkinsburg, county of Allegheny, and State of Pennsylvania, and JOHN F. BAILEY, a citizen of the United States, residing at Edgewood, county of Allegheny, and State of Pennsylvania, have invented a new, original, and ornamental Design for Urinals, of which the following is a specification, reference being had to the accompanying drawing, forming a part thereof.

The drawing is a perspective view of a urinal showing our new design.

We claim:

The ornamental design for a urinal, as shown.

OLIVER C. G. BRETELL.
JOHN F. BAILEY.

Witnesses:

ROBT. D. TOTTEN,
J. F. WILL.
